RAZOR BLADE SHARPENER

William A. Campbell, Youngstown, Ohio

Application July 7, 1936, Serial No. 89,439

5 Claims. (Cl. 51—65)

This invention relates to razor sharpeners and holders and has for the primary object the provision of a simple and inexpensive device of this character whereby a razor may be rapidly and 5 efficiently sharpened and employs a reciprocating sharpening element and holder for the razor to maintain the blade thereof in proper relation and with desired pressure on the sharpening element and which will automatically change the position 10 of the blade or present the opposite side of the blade on the sharpening element as the latter completes its movement in one direction and starts in a reverse or opposite direction.

With these and other objects in view, this invention consists in certain novel features of construction, combination and arrangement of parts to be hereinafter more fully described and claimed.

For a complete understanding of my invention, reference is to be had to the following description and accompanying drawings, in which—

Figure 1 is a top plan view illustrating a razor sharpener constructed in accordance with my invention.

Figure 2 is a side elevation illustrating the same.

Figure 3 is a longitudinal sectional view illustrating the means for reciprocating the sharpening element and the means of shifting the position 30 of the blade of the razor relative to the sharpening element after the latter completes its movement in either direction.

Figure 4 is a transverse sectional view illustrating the device.

Figure 5 is a fragmentary sectional view taken on the line 5—5 of Figure 1.

Figure 6 is an end elevation, partly in section, illustrating the shifting element.

Figure 7 is a fragmentary side elevation illustrating the shifting element.

Figure 8 is a fragmentary sectional view illustrating a journal for one end of the razor holder and cooperates with stops in preventing the blade after each shifting operation thereof from contacting the sharpening element until such time as the sharpening element reverses its direction of travel.

Referring in detail to the drawings, the numeral 1 indicates a casing which may be equipped 50 with a removable cover (not shown). The end walls of the casing, indicated by the character 2, have mounted thereon bearings 3 rotatably supporting a feed shaft 4. The feed shaft has oppositely extending feed threads 5, also has secured to one end a gear 6 meshing with a gear 7

secured to a crank handle 8. The crank handle is arranged exteriorly of the casing and is journaled to one of the end walls thereof for the purpose of rotating the feed shaft in a clockwise direction.

A carriage 9 is slidably mounted on the feed shaft by bearings 10 and is provided with legs 11 which slide against the bottom of the casing for maintaining the carriage horizontally. A spring pressed feed nut 12 is slidably secured to the carriage by a bracket 13 and meshes with the feed threads 5 of the feed shaft 4. The rotation of the feed shaft with the feed nut 12 in engagement with the threads thereof brings about a reciprocation of the carriage. A sharpening element 14 is suitably secured to the carriage and is of plate-like formation.

Arranged transversely of the casing and rotatably supported by the side walls of said casing is a chuck or razor holder 15, a portion of which 20 is in the form of a shaft 16 having a groove 17 therein to receive the non-cutting edge of a razor. A bearing-like portion 18 is secured to the shaft 16 adjacent one end and is journaled in one of the side walls of the casing and has formed thereon a disc 19. The disc is equipped with a notch 20 aligning with the groove 17. The notch 20 also extends into the bearing-like portion 18 and the purpose of which is to receive the shank of the razor blade so that the handle, indicated by the character 21, may be positioned exteriorly of the casing with the blade positioned inside of the casing and transversely of the sharpener 14.

A bearing 22 is formed on the other end of the shaft and is rotatably supported by the other side wall of the casing and has formed therein oppositely extending arms 23 to which are pivoted hook-shaped elements 24. The hook-shaped elements 24 extend in opposite directions relative to the shaft 16 and have connected thereto coil 40 springs 25. The springs 25 are secured to the end walls of the casing. The springs due to their connection with the holder 15 alternately act to exert a turning action to the holder for the purpose of bringing the blade in contact with the sharpening element with desired pressure. A segmental shaped plate 27 is secured to the bearing 22 and has secured thereon pins 28, which pins extend in opposite directions to each other. Hook-shaped members 29 are secured to opposite ends 45 of the carriage 9 and each has a cam-shaped end 30, the purpose of which is to engage the pins 28 for the purpose of rotating the holder 15 in either direction to present first one side of the blade of the razor against the sharpening element 55

Referring in detail to the drawings, the numeral 1 indicates a casing which may be equipped 50 with a removable cover (not shown). The end walls of the casing, indicated by the character 2, have mounted thereon bearings 3 rotatably supporting a feed shaft 4. The feed shaft has oppositely extending feed threads 5, also has secured to one end a gear 6 meshing with a gear 7

and then the other side of the blade after the holder completes its movement in either direction.

Set bolts 31 are threaded to the disc 19 and enter the notch 20 thereof to engage the shank 5 of the razor blade and thereby secure the blade in the holder 15.

In operation, the crank handle 8 is rotated in a clockwise direction causing the carriage to reciprocate. As the carriage reaches substantially 10 the end of its movement in one direction one of the hook-shaped members 29 engages one of the pins and imparts rotation to the holder 15 to present the other side of the blade against the sharpening element. When the carriage nears 15 the limit of its movement in an opposite direction the other hook-shaped member 29 engages the other pin 28 and rotates the holder 15 in an opposite direction to present the other side of the blade against the sharpening element.

20 Pins 32 are secured to the disc 19 and they coact with stops 33 arranged at opposite ends of the carriage, the purpose of which is to prevent the blade or the cutting edge from being presented in engagement with the sharpening element after the shifting of the position of the blade and prior to the carriage reaching the limit of its movement in either direction. However, as soon as the carriage starts in a reverse direction the stop which is contacted by one of the 25 pins becomes disengaged therefrom allowing the cutting edge of the blade to contact the sharpening element at a proper angle.

Having described the invention, I claim:

1. A razor sharpener comprising a casing, a 30 carriage slidably mounted in said casing, a continuously rotatable feed shaft journaled in said casing and having double threads reversely arranged to each other thereon, a feed nut carried by the carriage for reciprocating the same, a 35 sharpening element carried by the carriage, a holder journaled to the casing for supporting a blade at a proper angle to the sharpening element, automatic means for rotating the holder in either direction for the purpose of changing the position of the blade to present first one side thereof to the sharpening element and then the other side, said last-named means acting when the carriage reaches substantially the limit of its movement in either direction to bring about 40 a reversing of the blade on the sharpening element when the carriage reaches the limit of its movement in one direction and starts to move in an opposite direction, and stop means carried by the holder and carriage coacting adjacent to 45 the ends of the reciprocatory movements of the carriage for maintaining the blade elevated above the sharpening element during reversing movements of the carriage.

2. A razor sharpener comprising a casing, a 50 carriage slidably in said casing, a feed shaft journaled in the casing and having double feed threads reversely arranged to each other, a feed nut carried by the carriage and engaging the feed threads whereby said carriage will be reciprocated by the rotation of the shaft in one 55 direction, means for rotating the shaft, a sharpener carried by the carriage, a holder journaled

in the casing for supporting a razor blade, and means in the casing coacting with the carriage for positioning the blade in proper relation to the sharpening element.

3. A razor sharpener comprising a casing, a 5 sharpener mounted for reciprocation in the casing, continuously rotating means for effecting the reciprocating movements of said sharpener, a holder mounted in the casing and arranged transversely of the sharpener for supporting a blade 10 in contact with the sharpener, oppositely extending arms secured to the holder, hook-shaped elements pivoted to said arms and extending in opposite directions, coil springs connected to said hook-shaped elements and to the ends of the 15 casing, and means operated by the movement of the sharpener to rotate the holder in opposite directions to alternately present opposite sides of the blade against the sharpening element when the sharpening element nears the end of its movement in either direction.

4. A razor sharpener comprising a casing, a sharpener mounted for reciprocation in the casing, continuously rotating means for effecting the reciprocating movements of said sharpener, a 25 holder mounted in the casing and arranged transversely of the sharpener for supporting a blade in contact with the sharpener, oppositely extending arms secured to the holder, hook-shaped elements pivoted to said arms and extending in opposite directions, coil springs connected to said hook-shaped elements and to the 30 ends of the casing, spaced pins secured to the holder and extending in opposite directions, and hook-shaped members secured to opposite ends 35 of the sharpener to engage said pins for rotating the holder in an opposite direction by movement of the sharpener for alternately presenting opposite sides of the blade against the sharpener when the latter nears completion of its movement in either direction.

5. A razor sharpener comprising a casing, a carriage slidably mounted in the casing, continuously rotating means for effecting the reciprocating movements of said carriage, a sharpening element carried by the carriage, a holder 45 arranged transversely to the sharpening element and journaled in the casing for supporting a razor blade in proper relation to the sharpening element, spring means connected to the holder, pins secured to the holder, means carried by the 50 carriage for alternately engaging said pins to alternately present opposite sides of the blade to the sharpening element during each completion of movement of the carriage in each direction, means for securing the razor to the holder, pins carried by said holder, and stops located at the 55 ends of the carriage to be engaged by the last-named pins to prevent the holder from contacting the cutting edge of the blade with the sharpening element after each operation of the holder for presenting opposite sides of the blade to the sharpening element until such time as the carriage completes its movement in one direction and starts to move in a reverse direction.

WILLIAM A. CAMPBELL.
